UNITED STATES PATENT OFFICE.

HENRY E. VAN NESS, OF ELMIRA, NEW YORK.

TENSION DEVICE.

Application filed July 20, 1922. Serial No. 576,249.

To all whom it may concern:

Be it known that I, HENRY E. VAN NESS, a citizen of the United States, residing at Elmira, in the county of Chemung and State of New York, have invented certain new and useful Improvements in Tension Devices, fully described and represented in the following specification and the accompanying drawings, forming a part of the

10 same.

This invention relates to tension devices and method of threading the same, and particularly to the type in which a drag or tension is applied to a yarn, or the like, by drawing the material between an upper rotary tension member and a lower supporting member.

An object of the invention is to provide a tension device of this character which may 20 be threaded quickly and easily.

A further object of the invention is to provide a device which will cause a smooth even tension upon the yarn.

In tension devices of the type in question 25 which have heretofore been used, it has been necessary to position the yarn accurately at, or near, the lower edge of the tension member in order to draw it under this member in threading a device. The operation 30 of threading has in consequence required considerable care and time on the part of the operator.

A tension device constructed in accordance with the present invention may be 35 threaded by simply laying the yarn across the top of the device. The tension member is so formed, and the yarn is so guided, that when the pull of a winding machine is applied to yarn laid across the top of the device the yarn is automatically positioned between the supporting member and the tension member.

Other features and advantages of the invention are hereinafter pointed out in connection with a detailed description of the embodiments of the invention illustrated in the accompanying drawings, in which:—

Fig. 1 is a plan view of a tension device embodying the invention applied to a frame 50 which may contain a yarn cleaner, showing the position in which the yarn is drawn across the device when a pull is first applied to the yarn after threading the tension device;

Fig. 2 is a side elevation of the tension

device and frame shown in Fig. 1 showing the yarn in the same position;

Figs. 3 and 4 are views similar to Figs. 1 and 2 showing the yarn in the position into which it is drawn as the pull on the yarn is continued;

Figs. 5 and 6 are views similar to Figs. 1 and 2, showing the final position into which the yarn is drawn by a pull applied to it;

Fig. 7 is a rear end view of the tension device and frame shown in Figs. 1 to 6;

Fig. 8 is an enlarged plan view of the tension device shown in Figs. 1 to 7;

Fig. 9 is a transverse section of the device on the line 9—9 of Fig. 8;

Fig. 10 is a perspective view of the tension member;

Fig. 11 is a perspective view of one of the weight discs;

Fig. 12 is a plan view of a modified form 75 of tension device in which the supporting member is rotary; and

Fig. 13 is a side view, partly in section, of the device shown in Fig. 12.

The apparatus illustrated in Figs. 1 to 7 80 includes a rectangular frame 10. The front end member 11 of the frame contains a recess 12 at its middle and the rear end member 13 contains a similar recess 14. The frame 10 is provided with cover plates 15, 85 16 whose inner edges are spaced apart to provide a slot 17 extending between the recesses 12 and 13. On the rear end member 13 is mounted a rear guide 18 which serves to draw a yarn down below the level of the bottom of the recess 14. The rear guide 18 90 may, if desired, be mounted upon the frame of a winding machine to which the frame 10 is attached, instead of upon the rear end member 13 of the frame 10, as shown.

The frame 10 may contain elements adapted to clean a yarn drawn across the frame, such as are shown in my co-pending application filed June 8, 1922, Serial No. 566,722, of which this application is a continuation 100 in part. As, however, these elements form no part of the invention covered by the present application, they are not shown or described herein.

On the front end member 11 of the frame 105 10 is mounted a plate 20. The inner end of this plate is bent to form an upward projection 21 which may be screwed to the end member 11 of the frame. The projection 21 contains a central recess 22 registering with 110

the recess 12. The upper surface of the plate 20 lies on a level with the bottoms of the recesses 12 and 14.

A stud 30 projects upwardly from the plate 20. The stud has a cylindrical shank 31 and is positioned so that this shank is tangential to the center line of the recesses 12 and 14. The stud has at its top a flange or head 32.

10 A rotary tension member 40 is seated on the plate 20 about the stud 30. This tension member is cup-shaped and has a disc-shaped bottom 41 and a wide flaring flange 42 extending outwardly and upwardly from the periphery of its bottom. The bottom 41 contains a central circular hole of sufficient size to pass over the head 32 of the stud 30. As best seen in Fig. 9, the bottom 41 is curved upwardly so that its lower surface is slightly 15 concave. The flange 42 most desirably has the shape of a frustum of a cone, as shown. Its width is preferably as great or greater than the radius of the bottom 41. When the tension member is seated on the plate 20, 20 its flange 42 extends upwardly above the top of the stud 30.

The portion 25 of the plate 20 which is under the bottom 41 of the tension member 40 constitutes the supporting member of 30 the tension device against which a yarn is pressed by the tension member when the device is in operation. The portion 26 of the plate 20 which lies in front and at one side of the supporting member 25 constitutes the 35 front guide of the tension device. The front guide 26 contains a recess 27 whose inner end is located under the flange 42 of the tension member and in a line passing through the centers of the recesses 12 and 14 and tangential to the stud shank 31. The outer ends of the front guide 26 at each side of the recess 27 may be turned up to form ears 28 to aid in placing a yarn in the recess 27 when the device is threaded. It is important 40 that the portions of the front guide 26 which lie, respectively, immediately in front of, and at the side of, the supporting member 25 have their upper surfaces at the same level as the upper surface of the supporting member 25. It is, however, not essential 45 that the front guide and the supporting member be made of a single plate as illustrated in Figs. 1 to 9.

A plurality of weight discs 50, each containing a central hole 51, are provided to 50 vary the tension upon the yarn. Any desired number of these discs may be placed in the tension member 40 so that they rest upon its bottom 41.

60 In order to prevent accidental removal of the rotary tension member, and in particular to prevent this member from flying off the stud 30 in case a large slug on the yarn enters under the bottom 41, locking 65 means are provided between the weight discs

50 and the head 32 of the stud 30. For this purpose, the head 32 of the stud is made non-circular in outline and the central holes 51 of the weight discs 50 are given a similar non-circular outline. Consequently, the 70 weight discs may be passed over the head of the stud when turned in one direction. After they fall down about the cylindrical shank of the stud, they soon become turned so that their non-circular openings do not 75 register with the head of the stud. When, therefore, the tension member is thrown upward for any reason, the weight discs engage the head of the stud and prevent the tension member from coming off the stud. 80

The use and operation of the tension device which has been described is as follows: The device is threaded by laying a yarn A across the top of it. To do this it is merely necessary to drop the yarn between the ears 28 of the front guide and across the top of the tension member 40, and to pass it through the rear guide 18. When the yarn is thus dropped across the top of the device, it is slack, and consequently it may lie across any part of the top of the flange 42 of the tension member 40. As, however, the flange 42 projects above the top of the stud 30, the yarn cannot catch on the stud. Consequently, 90 when the pull of a winding or other machine is applied to the yarn to draw it in the direction indicated by the arrows in the drawing, the yarn is immediately drawn into the position shown in Figs. 1 and 2. It should be noted that the yarn is guided through a point B at or near the inner end of the recess 27 in the front guide and through a point C at the bottom of the recess 14. The point B is located in front of the tension member 40 and the supporting member 25 and at the level of the upper surface of the supporting member 25. The point C is located at some distance behind the tension member and the supporting member and at a level with the upper surface of the supporting member. The points B and C lie on a line crossing the tension and supporting members at one side of the axis of rotation of the tension member. This line lies on the same side of the axis of the tension member as the side portion of the front guide 26. As the result, the yarn is drawn across the top of the tension member 40 at this side of the axis of the member. As the 100 pull on the yarn continues, the yarn turns the tension member in a clockwise direction looking from the top. As a result, the yarn is first brought into the position shown in Figs. 3 and 4, and then slips off the upper edge of the flange 42 of the tension member and is guided by the under surface of the flange, and to some extent also by the flat surface of the front guide, so that it is drawn in between the bottom 41 of the tension member and the upper surface of the 105 110 115 120 125 130

supporting member 25 until it occupies the position shown in Figs. 5 and 6. As the yarn is drawn forward after it has been brought into this position, an even tension is applied to it by the weight of the tension member 40, and the degree of this tension may be varied at will by placing any desired number of weight discs 50 in the tension member. The fact that the bottom surface of the tension member is slightly concave has been found to add materially to the evenness of the tension. This is believed to be due to two reasons. The first is that when the device is in operation, the tension member 40 is supported at only three points, all of which are near the periphery of its bottom 41. The second is that the yarn is not drawn across any sharp edges, since the edges of the hole in the center of the bottom 41 are above, and out of contact with, the yarn.

Figs. 12 and 13 illustrate a modified embodiment of the invention in which the supporting member of the tension device is 25 rotary. The tension device illustrated in Figs. 12 and 13 includes a frame 20'. On the upper side of the frame is a boss 23. A stud 30' projects upwardly from this boss. The supporting member 25' of the tension 30 device is, in this case, separate from the frame 20'. It contains a central hole surrounding the lower portion of the stud 30', rests upon the boss 23, and is rotatable. A 35 rotary cup-shaped tension member 40' similar to the tension member 40 is seated on the supporting member 25' about the stud 30'. Its flange 42' extends upwardly above the top of the stud 30'. The front guide 26' may be formed integral with the frame 20' 40 and provides a flat surface at the level of the top of the supporting member 25' and extending around the front and one side of the supporting member. The front guide 26' contains a recess 27' whose inner end extends under the flange 42' of the rotary tension member 40'. The front guide provides horizontal ears 28' at each side of a recess 27'.

A rear guide 18' is mounted on the rear portion of the frame 20'. The rear guide is positioned and formed to direct the yarn through a point C' located behind the tension and supporting members, on a level with the upper surface of the supporting member, and on a line passing through the inner end of the recess 27' and crossing the tension and supporting members at the same side of the axis of rotation of the tension member as the side portion of the front guide 26'.

The tension device just described operates in substantially the same manner as that first described. It may be threaded by merely dropping the yarn into the recess 27' and across the top of the flange 42' of the tension

member 40', and drawing it through the rear guide 18'.

From the above description, it is apparent that the present invention provides a tension device in which a yarn dropped across the top of the device is automatically introduced under the tension member as soon as a pull is applied to it. As it is believed this is a result which has never before been attained, it should be understood that the invention is by no means limited to the details of construction and arrangement shown in the drawings.

The tension device may be used in connection with any sort of yarn, thread, cord, twine, or similar material. In order to avoid unnecessary repetition, the word "yarn" is used in the specification, and in the claims which follow, in a generic sense and should be understood to include any type of yarn, thread, cord, or twine to which a tension is to be applied.

What is claimed is:

1. A tension device, comprising the combination of a frame containing aligned recesses in its ends to permit the passage of the yarn longitudinally across the frame, a plate projecting outwardly from the front end of the frame at the level of the bottoms of said recesses, said plate containing in its outer end an entrance recess aligned with the recesses in the frame, a stud projecting upwardly from said plate at one side of the center line of said recesses, and a rotary tension member seated on said plate about 90 said stud and having a disc-shaped bottom 95 and a flaring flange projecting upwardly and outwardly from the periphery of the bottom and extending over the inner end of said entrance recess and above the top of the frame. 100

2. A tension device, comprising a supporting member, a tension member rotatably mounted on said supporting member and having a disc-shaped bottom and a wide flaring flange extending outwardly and upwardly from the periphery of said bottom, a front guide providing a recess extending under the flange of the tension member and terminating outside the periphery of the bottom of the tension member, the device being formed and arranged to leave the top of the tension member unobstructed so that a yarn may be dropped into said recess and across the top of the tension member, and means for guiding a yarn laid in said recess and across the top of the tension member through a point located behind the tension member and on a line passing through the end of said recess and crossing the tension member at one side of its axis of rotation. 115 120 125

3. A tension device, comprising a supporting member, a stud projecting upwardly from said supporting member and having a cylindrical shank and a non-circular head, a rotary cup having a central hole 130

adapted to pass over said head, and a weight disc having a non-circular central hole adapted to pass over said head when turned in one direction.

5 4. In a tension device, a rotary tension member having a circular bottom and a flaring flange extending upwardly and outwardly from the periphery of said bottom and having the shape of an inverted truncated cone and having a width greater than the radius of the bottom.

5 5. A tension device comprising a supporting member, a stud projecting upwardly from said supporting member, and a tension member having a circular bottom and a flaring flange extending upwardly and outwardly from the periphery of said bottom, said bottom having an approximately spherically curved concave lower surface 20 and containing a central hole which fits loosely around said stud, a relatively narrow contacting peripheral edge being provided so that when a yarn is passed between the supporting member and the tension member the tension member is supported at three points all of which are located upon the relatively narrow peripheral edge formed at the juncture of the circular bottom with the flaring flange.

30 6. A tension device, comprising a supporting member, a stud projecting upwardly from said supporting member, a tension member having a circular bottom containing a central hole fitting loosely around said stud and a wide flaring flange extending upwardly and outwardly from the periphery of said bottom, the device being formed and arranged to leave the top of the tension member unobstructed so that a yarn may be dropped 35 across it, and means for guiding a yarn laid across the top of the tension member through two points located respectively in front and behind said members, on a line crossing said members at one side of the 40 axis of rotation of the tension member, and below the top of the tension member.

7. A tension device, comprising a supporting member, a tension member rotatably mounted on said supporting member 50 and having sides which flare outwardly towards its top, the device being formed and arranged to leave the top of the tension member unobstructed so that a yarn may be dropped across it, and means for guiding a yarn laid across the top of the tension member through two points located respectively in front and behind said members and on a line crossing said members at one side 55 of the axis of rotation of the tension member.

60 8. A tension device, comprising a supporting member, a tension member rotat-

ably mounted on said supporting member and having sides which flare outwardly towards its top, the device being formed and arranged to leave the top of the tension member unobstructed so that a yarn may be dropped across it, and means for guiding a yarn laid across the top of the tension member through two points located respectively in front and behind said members, as low as the upper surface of the supporting member, and on a line crossing said members at one side of the axis of rotation of the tension member. 75

9. A tension device, comprising a supporting member, a tension member rotatably mounted on said supporting member and having sides flaring outwardly towards its top, means providing a guiding surface 80 on a level with the surface of the supporting member and located at one side thereof, the device being formed and arranged to leave the top of the tension member unobstructed so that a yarn may be dropped across it, and means for guiding a yarn laid across the top of the tension member through two points located respectively in front and behind said members, as low as the upper surface of the supporting member, and on a line crossing said members 85 on the same side of the axis of rotation of the tension member as said guiding surface. 90

10. A tension device, comprising a supporting member, a stud projecting upwardly from said supporting member, a tension member having a disc-shaped bottom seated on said supporting member and containing a central hole encircling said stud and a flaring flange extending upwardly from the periphery of its bottom and above the top of said stud, the device being formed and arranged to leave the top of said tension member unobstructed 100 so that a yarn may be dropped across it, and means for guiding a yarn laid across said tension member through two points located respectively in front and behind said members and on a line crossing said members at one side of the axis of rotation of the tension member. 105

11. A method of threading a tension device having an upper rotary tension member, which comprises laying a yarn across the top of the tension member, and drawing the yarn forwardly and downwardly along a line at one side of the axis of the tension member so that the yarn rotates the tension member until it slips over the upper edge thereof. 115

In testimony whereof I have hereunto set my hand.

HENRY E. VAN NESS.
